UNITED STATES PATENT OFFICE.

CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

CONDENSING APPARATUS.

Application filed August 5, 1925. Serial No. 48,241.

This invention relates to steam condensers of the surface type, the especial object of the invention being to provide a construction of high vacuum surface condenser adapted especially for large sizes, in which each of the condenser tubes shall contribute the maximum area possible to active condensation of steam and thus reduce to a minimum the total tube surface required for a given rate of steam per hour.

In carrying out the invention, I aim especially to minimize the pressure drop between the tubes in the steam and air zones by a short path and by causing the steam to sweep all the tube surfaces substantially equally, so as to prevent any sluggish flow in any region, and to equalize the pressure drop across the steam flow paths between the tubes throughout the condenser by making these steam paths substantially equal in flow resistance. I aim, also, to present to the incoming steam a large percentage of the total condenser tubes so as to secure the maximum of condensing activity and to make this percentage of tubes presented to the incoming steam substantially constant and independent of the size of the condenser.

In attaining these specific objects, the condenser tubes are disposed in the form of a belt through which the steam passes from one side to the other, the flow resistance through this belt being uniform so that the steam will not pass through portions of the belt more freely than through other portions. The tubes in the belt may be uniform in number and spacing of tubes from the entrance side to the exit side, or the tubes may be spaced more closely on the exit side, it being necessary only that the flow resistance from the inlet to the outlet side should be the same throughout the length of the belt. Other means, however, may be employed for securing the uniform resistance to flow across the belt that is important for securing the result of uniform flow and maximum condensation from each of the tubes. This desired result of uniform flow and maximum condensation from each of the tubes may be secured by a thinner belt of tubes closely spaced or a thicker belt of tubes more widely spaced. The belt will preferably be formed in folds or convolutions to provide large tube area within a certain condenser dimension with free admission of steam to a large percentage of the tube surface, and these folds or convolutions may be of any suitable shape and

adapted to a shell of any desired form. The folds or convolutions will be so arranged as to provide equal access of steam to all the tubes of the outer row on the steam side of the belt and so as to provide equal freedom of escape of air from all the tubes on the outlet or air side of the belt. It is preferable that all steam flow areas should be proportioned to the number of tubes supplied by steam from any particular section of the steam flow passage, so that the steam velocity will be the same in entering the tube belt and likewise the air spaces between the tube folds will preferably be widest at the exit end of the air passage, which aids in securing a compact construction and reducing the total size of the condenser.

In accordance with the present invention, the general features described above are arranged in such a manner that the steam is admitted on substantially all sides of the tube bank formed by the belt and the air taken off from the inside of the tube bank, thus securing the maximum condensing action of the tubes and providing for the maximum effective tube surface within given dimensions. This arrangement provides also for free access of exhaust steam to the falling condensate and hot-well and prevents the air separated out by condensation from coming into contact with the condensate falling from the tube bank and with the hot-well water, thus delivering the condensate at a temperature as near the temperature of the exhaust steam as possible and preventing the partial air pressure in the hot-well being increased and the temperature of the condensate thus lowered by contact of such air. The broader features of the invention may be embodied in constructions not employing an air cooler within the condenser, but preferably I arrange the tube bank so as to provide for an air cooler within the tube bank through which the air is drawn from the outlet side to the air outlet.

For a full understanding of the invention, there are shown in the accompanying drawings forming a part of this specification forms of condensers embodying my invention in preferred forms, and these constructions will now be described in detail and the features forming the invention then be specifically pointed out in the claims. In the drawings—

Figure 1 is a diagrammatic cross-sectional view showing a simple form of condenser em-

bodying the broader features of the invention without the air cooler within the tube bank;

Figures 2, 3, 4, 5, 6, 7 show modified forms of the same general character as shown in Fig. 1; and

Figures 8, 9 and 10 show modifications including an air cooler within the tube bank.

Referring to the drawings, A is the condenser shell, B the steam inlet, C the hot-well, and *a* the air offtakes, two being shown, for which the arrangement shown in Fig. 1 is well adapted. It will be understood, however, that a single air offtake may be used, or more than two air offtakes in large condensers, if desired, and the same applies to the other constructions hereafter described. These offtakes preferably are pipes extending through the air chamber and perforated or slotted to receive air throughout their length, and connected outside the condenser casing to the usual air ejector or vacuum pump of any form. The tube belt D, as shown in Fig. 1, is a shallow continuous bank of tubes, shown as of uniform depth, in which case the spacing of the tubes will be uniform throughout the belt. The tube belt is formed in several folds or convolutions, the steam inlet spaces 10 being preferably of decreasing width within the folds, according to the extent of the tube belt to be supplied with steam by the different sections of the inlet passage, thus securing a more compact construction and aiding in securing a uniform flow through the belt, and the air passages 11 on the opposite sides of the belt from the steam spaces will preferably expand, increasing in size toward the outlet, for free flow of air, with compactness of construction. It will be understood, however, that it is necessary only that the air spaces should be such as to secure the prompt and free flow of air from the outlet side of the tube belt.

It is not necessary that the number and spacing of the tubes should be uniform from inlet to outlet side of the belt, and in some cases it may be desirable to place the tubes nearer each other on the outlet side or to gradually decrease the tube spacing from the inlet to the outlet side, or otherwise provide for less free flow on the outlet side than on the inlet side of the belt. The decrease in tube spacing toward the outlet side allows for the steam condensed nearer the inlet side and the maximum condensation from each tube is thus secured with a large tube surface in the least condenser dimensions or with a reduction in condenser size.

The tube belt is formed so as to entirely enclose the air outlets *a* and the tube bank formed thereby is separated from the casing

A on all sides, so as to form a steam space 12 entirely surrounding the tube bank, so that the steam has access to all the tubes in the outer layer of the tube bank and to the falling condensate in the lower part of the con-

denser and the hot-well, the steam spaces 12 on opposite sides of the tube bank avoiding dead ends and securing the free circulation of steam through the lower part of the condenser and over the hot-well.

In Figs. 2, 3 and 4 the tube banks are of the same character as shown in Fig. 1, the specific form of the tube folds and the arrangement of the air offtakes being varied for condenser casings of different shape.

In some cases, and especially in large condensers, it may be desirable to use more than one tube belt, and such a construction with two tube belts is shown in Fig. 5, these two tube belts being arranged on opposite sides of the vertical central line of the condenser so as to leave a central passage 13 between them through which exhaust steam may pass directly to the bottom of the condenser and hot-well, as well as through the side passages 85 or spaces 12 around the tube banks.

In Fig. 6 a bowl-shaped condenser is shown, with a plurality of tube banks each formed by a separate belt, these tube banks being semicircular and nested together with steam spaces 10 between them for the admission of exhaust steam and with the air passages between the folds of each bank opening to separate air offtakes.

In Fig. 7 a rectangular condenser casing is shown with the tube belt formed to provide a bank at each side of the condenser, but the belt being continuous so as to close the central steam space to the hot-well and each bank being provided with one or more air offtakes *a*.

In Figs. 8, 9 and 10 there are shown tube banks of the same general character as those shown in the other figures and previously described, except that the belt folds are formed so as to leave a central space within the tube bank in which is contained an air cooler 14 covered by a plate 15 which shields the air cooler from the condensate and directs the air around the bottom edges of the plate to the lower part of the air cooler, through which the air passes upward to the air offtake *a*. Other forms of air cooler and cover plates may be used, the essential feature of this specific part of the invention being that the air cooler shall be within the tube bank.

It will be understood that the invention may be embodied in many other constructions differing in form and arrangement from those shown, and that the invention is not to be limited to the constructions illustrated, but includes all other constructions within the scope of the invention as defined by the claims.

What is claimed is:

1. In a steam condenser, a tube tank consisting of a continuous shallow belt of tubes being arranged in folds providing contracting steam spaces on the inlet sides of the folds and expanding air spaces on the exit

sides of the folds and an air outlet within the belt of tubes and communicating with said expanding air spaces.

2. In a steam condenser, a tube bank consisting of a continuous shallow belt of tubes being arranged in folds providing contracting steam spaces on the inlet sides of the folds and expanding air spaces on the exit sides of the folds and an air outlet within the belt of tubes and communicating with said air spaces, a hot well for receiving condensate, and a length of said continuous tube belt extending between said air outlet and hot well.

15. 3. In a steam condenser, a tube bank con-

sisting of a continuous shallow belt of tubes enclosing the air outlet and surrounded by a steam space, said belt of tubes being arranged in folds providing contracting steam spaces on the inlet sides of the folds and expanding air spaces on the exit sides of the folds, a hot well for receiving condensate, and a length of said tube belt extending between the air outlet and hot well and arranged to provide a space for passage of steam from 20 said steam space to the hot well.

In testimony whereof, I have hereunto set my hand.

CHARLES E. LUCKE.
